UNITED STATES PATENT OFFICE.

OTIS ALLEN KENYON, OF NEW YORK, N. Y.

MEANS OF PRODUCING CONSTANT-CURRENT REGULATION OF GENERATORS.

1,404,442.

Specification of Letters Patent. Patented Jan. 24, 1922.

Application filed January 22, 1918. Serial No. 213,137.

To all whom it may concern:

Be it known that I, OTIS A. KENYON, a citizen of the United States, residing at New York city, in the county of New York and State of New York, have invented certain new and useful Improvements in Means of Producing Constant-Current Regulation of Generators, of which the following is a specification.

10 My invention relates to an improved means of producing constant-current regulation in a direct current separately excited generator, and the invention consists of the parts and the constructions, arrangements 15 and combinations of parts which I will hereinafter describe and claim.

In the accompanying drawing forming part of this specification; Figure 1 illustrates more or less diagrammatically, a differential 20 regulator circuit system designed primarily for arc welding machines. Figure 2 illustrates a modified arrangement, to be herein-after disclosed.

In the said drawing 1 represents the armature of a constant-current generator; 2 is the shunt field thereof; 3, 14 and 15 are welding arcs in the main line; 4, 5 represent a carbon pile of suitable construction; 7 and 8 are plungers arranged in parallelism; and 30 6 is a yoke or part having stems passing through the plungers and having an intermediate member 6' which bears against the carbon pile; 9 is a series coil; 10 is a separately excited coil; 11 is a rheostat; and 12 35 is a separate source of electric energy.

For the purpose of electric arc welding, it is desirable to employ a source of constant-current, which is capable of maintaining a high degree of current regulation under extremely large and sudden variations 40 in the current. It is also desirable to have a suitable means for adjusting the value of the current over a wide range.

Constant-current generators such as are 45 used for series arc lighting, and which are generally known in the art, are not suited for arc welding, because the means employed for maintaining the constant-current characteristics are too slow to prevent large 50 momentary variations in the current, that will injure the metal.

My present invention has particular reference to an improved means of producing constant-current regulation in a direct current shunt wound generator. Preferably, I

employ a generator with a thoroughly laminated magnetic circuit constructed with interpole windings so as to obtain satisfactory commutation. The field of the generator I propose to excite from a separate 60 source, preferably low in voltage and insert in series with said excitation winding, a resistance, the value of which is varied by means actuated from the main line current.

I am aware that a similar method has been 65 used and is known in the art for the regulation of current in charging batteries. However, in battery work, there are no sudden variations, either in the current or in the E. M. F., and the important function 70 of such a regulator is to produce a very accurate and permanent degree of regulation.

In arc welding, a regulator is required which will maintain the constant value of 75 current under widely differing E. M. F.'s, which change suddenly from one value to another. Accuracy and permanency of adjustment are of no special value.

Heretofore, in the construction of regulators of the character described, the magnetic circuit of the regulator has been so constructed as to produce a constant pull over the entire working range and which is usually opposed by a constant force of 80 gravity and damped by a dashpot so as to prevent overswinging; it is also the practice to multiply all motions by some system of leverage.

In case of arc welding, such construction 90 as last referred to, is fundamentally wrong, and produces results that cannot be tolerated if the best results are to be expected, as will be understood from the following:

First of all it is necessary to reduce the 95 mass of moving parts to a minimum and, therefore, it is desirable to eliminate all levers and abolish dashpots and the use of gravity as an opposing force. It is also desirable to employ a means of adjusting the 100 operating point of the regulator so that it can be set to maintain a current in the main circuit at any desired value.

A leading object of the present invention is to provide a means of adjusting accurately 105 over a wide range the current at which the regulator operates, and in the illustrated embodiment of my invention, this idea is carried out, by using a carbon pile for the resistor in series with the excitation circuit, 110

and varying the pressure of said pile by a differential action between the two solenoid coils, 9 and 10, one excited from a source of constant-potential and the other carrying 5 the main line current which is to be regulated, the adjustment being made by varying the current in the constant-potential coil.

Referring to the drawing, Fig. 1, wherein 10 is illustrated an arc welding system, in which 3, 14 and 15 are arcs in series in the main line, and 1 is the armature of the constant-current generator, 9 is the series coil of the regulator, and 10, the separately excited coil thereof, it will be seen that the field 2 of the generator is designed to be excited from the separate source, 12, and connected in series with the carbon pile resistance, 4, 5. The value of the current in the 20 field, 2, is determined by the pressure exerted by the yoke, 6, on the pile, 4, 5, and this in turn is determined by the difference in pull exerted on the plungers 7, 8. The pull on the plunger, 8, of the coil, 10, is constant, 25 because said coil is connected across the source of constant-potential, 12. The pull of plunger, 8, is transmitted through yoke 6, and projection, 6', and acts to compress the carbon pile, 4, 5, thereby allowing the field current of winding, 2, to increase. If this 30 increase in field current and the consequent increase in E. M. F. of the generator results in an increase in the line or welding current, the pull of coil 9, will increase and by action 35 on the pile in opposition to coil, 10, cause the E. M. F. of the generator to decrease until the adjusted value of line current is established.

In this manner any change in the line 40 resistance or counter E. M. F. will be instantly counteracted by the automatic re-adjustment of the pressure on the pile, 4, 5, to give the exact balance of the two coils, 9 and 10.

By adjusting the rheostat, 11, in series 45 with the coil, 10, and which operation will be understood by those skilled in the art, the pull of the coil, 10, can be varied over any desired range and therewith the current in the main circuit supplied by the generator 50 armature, 1, can be varied at will. From this description it will be apparent that I have devised a means of adjusting accurately over a wide range, the current at which the regulator operates and that these 55 means include two coils and means controlled by the differential action thereof to regulate the current in the welding circuit, one of the coils being excited from a source of constant-potential and the other carrying 60 the main welding line current which is to be regulated.

Fig. 2 shows a different mechanical arrangement of the same operating parts as shown in Fig. 1. Instead of using a fixed 65 yoke, 6'', rocker arm, 19, pivotally balanced

at 18 is used. The plungers hang vertically from the ends of this rocker arm and swing in one direction or the other, according to the differential pull which is transmitted to the pile through pin, 17. Where heavy plungers are used, this mode of construction will greatly reduce the frictional resistance, and to a like extent improve the closeness of regulation.

Having thus described my invention what 75 I claim as new and desire to secure by Letters Patent is:—

1. An electric circuit, a solenoid coil connected in series therein, a constant potential circuit, a solenoid coil in series therein, and 80 means controlled by the differential action of said coils to regulate the current in the first mentioned circuit.

2. An electric circuit, a solenoid coil connected in series therein, a constant potential 85 circuit, a solenoid coil in series therein, and means for adjusting the current in said constant potential circuit, and means controlled by the differential action of the said coils to regulate the current in the first mentioned 90 circuit.

3. An electric generator having a separately excited field winding, a solenoid coil in series in the generator main circuit, a constant potential circuit and a solenoid coil in 95 series therein, and means controlled by the differential action of the said coils for varying the value of the current in the field winding of the generator.

4. An electric generator having a separately excited field winding, a solenoid coil in series in the generator main circuit, a constant potential circuit and a solenoid coil in 100 series therein, means for adjusting the current in the constant potential circuit, and 105 means controlled by the differential action of the said coils for varying the value of the current in the field winding of the generator.

5. An electric generator having a separately excited field winding, a device for varying the resistance of the excitation circuit, 110 a constant potential circuit, a solenoid coil excited thereby and adapted to actuate said device to maintain the excitation current at a certain value, and electro-responsive means 115 controlled by the generator current and adapted to oppose the action of the said solenoid.

6. An electric generator having a separately excited field winding, a device for varying the resistance of the excitation circuit, a constant potential circuit, a solenoid excited thereby and adapted to actuate said device to maintain the excitation current at a certain value, and means for adjusting this 120 value, and electro-responsive means controlled by the generator current and adapted to oppose the action of the said solenoid.

7. An electric generator having a separately excited field winding, a carbon pile in 125

- series in the excitation circuit, a solenoid coil in series in the generator main circuit, a constant potential circuit and a solenoid coil in series therein, and means for varying 5 the pressure on the carbon pile by the differential action between the said coils.
8. An electric generator having a separately excited field winding, a carbon pile in series in the excitation circuit, a solenoid coil 10 in series in the generator main circuit, a constant potential circuit and a solenoid coil in series therein, means for adjusting the current in the constant potential circuit, and means for varying the pressure on the said
- carbon pile by the differential action between 15 the said coils.
9. An electric generator having a separately excited field winding, a carbon pile adapted to vary the resistance of the excitation circuit, a constant potential circuit, a 20 rheostat in series therein, two solenoid coils, one in series in the generator main circuit, the other excited by the constant-potential current, and means controlled by the differential action of said coils, to vary the pres- 25 sure on said carbon pile.

In testimony whereof I affix my signature.
OTIS ALLEN KENYON.
